UNITED STATES PATENT OFFICE.

RALPH G. A. BECK, OF MONTREAL, QUEBEC, CANADA.

NIPPLE FOR NURSING BOTTLES AND THE LIKE.

Application filed October 14, 1927, Serial No. 226,143, and in Canada March 28, 1927.

This invention relates particularly to infants' nursing bottles of the type disclosed in my pending application Serial No. 177,035, now Patent No. 1,668,227 of which this application is a divisional part, and its primary object is to provide a new and improved nipple which is so constructed and arranged that it may be easily applied to and removed from the bottle neck and when in position thereon may be snugly interlocked therewith thereby obviating leakage and preventing accidental displacement when in use.

To this end my invention consists of the construction and particular arrangement of the parts hereinafter described and illustrated and pointed out in the claim.

In the accompanying drawings in which similar reference characters indicate the same parts:

Figure 1 is a side elevation of a nursing bottle constructed according to my invention;

Figure 2 is a fragmentary part elevation and part sectional view of the bottle neck with the nipple or teat mounted thereon;

Figure 3 is a partial elevation and partial section of the nipple detached from the bottle; and

Figures 4 and 5 are detail elevations of the nipple, a modification being shown in Figure 5.

Referring to these drawings which illustrate the preferred embodiment of my invention the bottle proper is indicated at 2, the comparatively short neck thereof at 3 and the nipple which is constructed and arranged to be stretched over the bottle mouth and interlocked therewith at 4.

Heretofore the nipple has been the source of constant trouble owing to its tendency to come off when in use, or to become so displaced as to cause leakage, and many attempts have been made to provide a solution of the problem. To my knowledge, however, none have proved entirely satisfactory and much difficulty is still being experienced with the various types of nipples now in use. The present invention seeks to overcome the problem by so constructing the bottle neck and the nipple that one will interlock with the other in such a manner that the possibility of the nipple becoming accidentally dislodged or displaced is positively prevented, in fact with the construction and arrangement of the parts hereinafter described it is impossible to pull the nipple off the bottle if it is grasped at its free end. The preferred embodiment for securing the foregoing desideratum consists of a pair of vertically spaced external collars 5 and 6, respectively, formed integrally with the bottle neck and encircling the same at the mouth thereof, and a pair of correspondingly spaced internal continuous beads 7 and 8 formed integrally with a skirt or band 9 on the nipple. This skirt or band consists of a comparatively thin elastic sleeve-like extension of uniform thickness joined to the bottom edge of and being of smaller diameter than the breast or shoulder portion 10 of the nipple and adapted to be stretched over the bottle neck, the band, when in position, snugly conforming to the irregular shape presented by the collars and extending downwardly for a short distance below the same.

In order to obtain the positive interlocking relationship hereinbefore referred to, the underside of each collar is recessed as at 11 in hooked form, and the dimensions and relative spacing of the beads on the nipple are such that when in position on the bottle the beads snugly fit within the recesses. It is obvious from this construction and arrangement of parts that any direct pull on the nipple away from the bottle will simply cause the nipple to grip the bottle more tightly. The interlocking relationship is clearly shown in section in Figure 2 and it will be noted that owing to the inherent elasticity of the band and the breast or shoulder portion the nipple snugly adheres to the rounded external surfaces of the collars indicated at 5¹ and 6¹ respectively so that a snubbing action at these points is obtained which further assists in preventing dislodgement of the beads from their respective grooves. The top collar 5 is rounded off as at 5² to facilitate the application of the nipple and merges with the bottle neck to form a flared mouth. The lower collar 6 does not project outwardly as far as the top collar, nor is its recess as deep, and its external surface is inclined upwardly and inwardly to the top recess as indicated at 12. The lower collar consequently tapers upwardly to the top collar in frusto-conical form so that if the lower nipple bead should become sufficiently displaced to slip over the lower collar it will slide along the inclined face 12 into the top recess. The beads are of substantially half-round cross-section and are respectively located at the junction of the top edge of the band and the bottom edge of

the breast or shoulder portion of the nipple and at a point a short distance below the same on the inner face of the band.

In view of the fact that the collars project 5 beyond the normal exterior of the neck and that the nipple positively interlocks therewith it is desirable to provide means for facilitating the application of the nipple and its removal from the bottle. To this end the band 10 has integrally formed therewith one or more downwardly extending tabs or lips 13 and 14, constituting fingerholds which may be grasped in the applying and removing operations. These lips are located diametrically 15 opposite one another and terminate in thickened edges 15, and their side edges are curved upwardly and outwardly as at 16 at the points at which such edges approach the bottom edge of the band thereby providing an increased 20 width at the junction of the tab with the band and obviating any danger of the band being torn or split when the nipple is peeled off the bottle.

In applying a nipple or teat constructed according to my invention one of the lips is clamped against the bottle neck with the forefinger of one hand while the band is distended sufficiently, by grasping the other lip with the other hand, until it can be pulled 30 over the collars to position in which the beads lie snugly within the recesses. In the re-

moval operation it is only necessary to grasp either one of the lips and peel it backward until the beads clear the collars.

Although this invention is primarily designed for use in connection with nursing bottles and the like it is to be distinctly understood that it may be embodied in other receptacles of like nature without departing from the spirit of the invention.

In certain types of bottles detachable rubber valves are fitted over valvular openings in the bottles at or adjacent to their bottom ends and it is obvious that the application of the interlocking feature and the fingerholds thereto is within the scope of the present invention.

What I claim is as follows:

A nursing bottle nipple, adapted to so interlock with the bottle neck as to prevent accidental displacement and comprising a skirt portion adapted to fit around the neck of the bottle and provided with a pair of vertically spaced internal beads adapted to engage under a pair of undercut collars on the bottle neck, and a pair of finger tabs extending downwardly from the edge of said skirt portion.

Signed at the city of Montreal, Province of Quebec, this third day of October, 1927.

RALPH G. A. BECK.
